UNITED STATES PATENT OFFICE.

WILLIAM H. WOOD, OF CLEVELAND, OHIO, ASSIGNOR TO STANLEY W. COOK, TRUSTEE,
OF CHICAGO, ILLINOIS.

APPLIANCE FOR CORRECTING FOOT AILMENTS.

1,243,124.

Specification of Letters Patent. Patented Oct. 16, 1917.

Application filed December 16, 1916. Serial No. 137,321.

To all whom it may concern:

Be it known that I, WILLIAM H. Wood, a citizen of the United States, residing at Cleveland, in the county of Cuyahoga and 5 State of Ohio, have invented certain new and useful Improvements in Appliances for Correcting Foot Ailments, of which the following is a specification.

My invention relates to appliances for 10 correcting foot ailments, and more particularly to means for alleviating or correcting falling of the transverse arch of the foot. It is a fact well recognized by foot specialists, that the anterior portions of one or 15 more of the metatarsal bones sometimes becomes displaced, tending to flatten the transverse arch of the foot adjacent the "ball" of the foot, thus causing local, and sometimes far-reaching, pain to the individual.

20 One of the objects of my invention is to provide an appliance for exerting a curative upward pressure on the under surface of the foot contiguous to the affected portion for mechanically restoring the displaced 25 metatarsal bone or bones to proper position, and further objects of my invention are to provide such an appliance in simple, inexpensive, practical form that will enable the appliance properly to be used by the 30 medially untrained individual and that will insure its retention in proper working position under the diversified conditions of normal uses of the foot.

In the drawings, wherein I have illustrated 35 for purposes of full disclosure one embodiment of my invention—

Figure 1 is a perspective view showing the appliance in use.

Fig. 2 is a transverse vertical section 40 through parts of the appliance.

Fig. 3 is a fragmentary plan view indicated by lines 3—3 of Fig. 2.

Fig. 4 is a view of the parts as seen from line 4—4 of Fig. 2, and

Fig. 5 is a detail of one of the parts detached.

In the embodiment of my invention I employ a "hump" plate 9 suitably shaped to act upon a small local area of the foot adjacent the heads of the affected metatarsal bones, this plate taking suitable form, herein illustrated as a sheet metal disk provided with a marginal flat annulus 10 and a central hump 11 of suitable contour in plan and section, the hump being convexo-concave

to provide therebeneath a recess 12. This "hump plate" is connected with a foot encircling girdle or belt 14, and the latter is suitably connected, as by stitching 15, with the top portion of a toe-envelop or "mitten" 17 that, covering the toe portion of the foot, anchors the belt and its connected hump plate against undue rearward displacement. Specifically I prefer that the mitten 17 shall be of woven fabric, chamois-skin or the like, comfortable to the foot, and that it shall, on its under side, be cut away as at 18, in front of the ball of the foot, its upper side extending rearwardly in a broad tongue 19, to a point in rear of the roots of the toes, partway up the instep of the wearer. The girdle or band 14, stitched to the mitten at this rearwardly extending tongue, preferably has its portion that extends under the foot, and that carries the hump plate, free for some adjustment, thereby lessening the necessary size-range permitting duplicate structures to be used by persons having feet of somewhat different size and toe-length.

I prefer that the girdle or belt 14 shall be a fabric or thin-leather strap adjustably held under desired tension by buckle-means positioned within the recess of the hump plate and engaging end portions of the strap. Specifically a simple arrangement, as shown in the drawings, will serve, the hump portion of the plate being provided with slots 21, diametrically opposed near the base of the hump, to receive the end-portions of the belt 14 that, within the recess of the hump plate respectively are passed around opposite cross-members of a metal loop 22, preferably toothed as at 23, the extremities of the belt-ends passing back through the apertures 21 as best shown in Fig. 2. Preferably the metal loop 22 has a transverse bar 24 for purposes to be described.

The structure thus far described may be used to advantage, as the toe-embracing mitten and associated belt will properly position the hump plate longitudinally of the foot, and the adjustment of the hump plate on the girdle or belt will properly position it laterally, so that the crest of the hump is beneath any selected metatarsal. In practice it is possible, in most cases, for the user to adjust the belt or girdle in the retaining means and to leave that adjustment, slipping the appliance on or off over the toes,

but if desired, the belt may be made slightly elastic for greater comfort of the wearer. In use the tendency of the hump plate is to slip backward, but this is adequately resisted by the joint action of the belt and toe-mitten.

In marketing my invention hump plates may, of course, be provided in different sizes and shapes, to vary the contour and 10 the height effective elevation, but to provide means most readily available for the user to effect change of the height of the hump I preferably provide, as an auxiliary to the device, means for attaching a pad 15 of desired thickness to the structure beneath the hump plate. Specifically the auxiliary "elevator" 30 is a thin metal plate, preferably made of spring metal, having downbent teeth 31 to engage a disk 32 of 20 suitable thickness, made of leather or other suitable material, a tongue 33 being struck from the plate 30 and bent to provide a transverse groove 34 extending across a diametrical line of the plate. Such plate may 25 have its grooved tongue engaged, as shown in Fig. 2, with the central transverse bar 24 of the buckle-loop, thereby firmly, but removably, to position the auxiliary elevator in register with the hump plate, the 30 rim of which will bear directly on the metal plate 30.

While I have herein described in some detail a particular embodiment of my invention it will be understood by those 35 skilled in the art that many changes in detail of construction and arrangement may be made without departure from the spirit of my invention and within the scope of the appended claims.

40 Having described my invention, what I claim is:—

1. The combination of a toe-enveloping structure, a belt connected therewith at the top of the structure, and a hump member 45 adapted to be positioned beneath the an-

terior portion of the metatarsals of the foot, connected with said belt.

2. The combination of a toe mitten, a buckled belt secured thereto, and a convexo-concaved hump plate mounted on said belt and receiving the buckle thereof in its concave.

3. The combination of a toe mitten, adapted to extend on its upper side beyond the toes partway up the instep, a belt connected 55 to the said top portion of said mitten and adapted to extend, free from said mitten, beneath the wearer's foot, and a hump element carried by said belt.

4. In a device of the character described 60 the combination of a foot encircling belt, a hump plate carried by said belt, and detachable means for elevating said hump plate.

5. In a device of the character described, 65 the combination of a convexo-concave hump plate, a strap for encircling the foot provided with a buckle, said buckle located within the concave of said hump plate, and means for elevating said hump plate at- 70 tached to said buckle.

6. In a device of the character described 75 the combination of a mitten to receive the toe portion of the foot, a belt connected to the upper portion of said mitten and provided with a buckle, a convexo-concave hump-plate receiving said buckle in its con- 80 cave, and an elevator comprising a plate having a spring tongue to engage the buckle and a padding below the plate.

7. In a device of the character described, 85 the combination of a convexo-concave hump-plate having opposed slots, a buckle in the concave of said hump, a strap passing through said slots and engaging the buckle, and a toe-mitten engaging said strap.

In testimony whereof I hereunto set my hand.

WILLIAM H. WOOD.
